UNITED STATES PATENT OFFICE.

GREEK F. BEASTON, OF COIN, IOWA, ASSIGNOR TO JOANNA McCRAKEN, OF COIN, IOWA.

CIRCUIT CLOSER.

Application filed June 3, 1925. Serial No. 34,671.

This invention relates to circuit closing devices especially adapted for use on automobiles.

Briefly stated, an important aim of this invention is to provide a circuit closing device for the starting motor of an automobile and which is operated by the spark control lever whereby to overcome the need of employing a separate foot operated switch.

10 A further object is to provide a circuit controlling device of the character specified which may be applied to an automobile either during the course of manufacture or at any time thereafter without the exercise 15 of unusual skill and without substantially altering the vehicle.

A further object is to provide a circuit controlling device which is of highly simplified construction, durable in use, and cheap 20 to manufacture.

Other objects and advantages will be apparent during the course of the following description.

In the accompanying drawing forming a 25 part of this application and in which like numerals are employed to designate like parts throughout the same.

Figure 1 is a perspective illustrating the application of the improved switch, the circuit and the starting motor also being illustrated;

Fig. 2 is a vertical sectional view through the improved switch;

Fig. 3 is an end elevation of the switch; 35 Fig. 4 is a perspective of a trigger embodied in the invention.

Fig. 5 is a fragmentary perspective view 40 illustrating the manner in which the invention may be carried out in connection with a Ford automobile;

Fig. 6 is a detail transverse sectional view taken on line 6—6 of Fig. 5;

Fig. 7 is a perspective of an actuating bar embodied in the invention;

45 In the drawing, wherein for the purpose of illustration is shown a preferred embodiment of the invention, the numeral 5 designates the improved switch consisting of a pair of approximately parallel normally spaced blocks 6 and 7 of insulating material.

Fig. 2 plainly illustrates that the blocks 6 and 7 have connection as indicated at 8 with the terminal portions of a U-shaped leaf spring 9. At this point it might be stated

50 that should the leaf spring become worn,

broken, or otherwise unfit for use, it may be quickly detached and renewed.

The numeral 10 designates the upper portion of one of the studs of the starter and as shown in Fig. 2 this stud extends through 60 and supports the insulating block 7 and the terminal portion of this stud constitutes a contact which is arranged in the path of travel of the head 15 of a binding screw 14. The binding screw 14 is adapted for 65 connection with the starter cable 18 by means of a clip or fastening member which is secured to the screw 14 beneath the block 6. The starter cable 18 has connection with the starting motor 20.

70 The movable block 6 is confined between and is held against lateral movement or side play by the sides of a rectangular guide member 28 rigidly secured as indicated at 30 to the fixed block 7. It will be seen that 75 when the contact 15 is moved into engagement with the contact head or terminal portion of the stud 10 the circuit will be completed for starting the motor 20 and thereby bringing about the turning of the fly wheel. 80

The rectangular guide 28 which is preferably constructed from flat metal an inch or so wide is provided with a slot 34 for the reception of an actuator bar 36, the inner terminal portion of which is provided with 85 a laterally projecting block engaging head 38. When the bar or lever 36 is swung in the direction of the block 6 the head 15 and the terminal portion of the stud 10 will be brought into engagement for closing the 90 electric circuit through the starting motor 20.

The actuating bar 36 is adapted to be swung to an operative position as shown in dotted lines in Fig. 2 by an arm 40 secured 95 to the spark control rod 41 by a clip 42. It will be seen that the rod 41 has the usual hand operated lever 44 which is moved downwardly to advance the spark and upwardly to retard the spark. Now when the spark lever 44 is manually retarded the arm 40 will move the actuating bar 36 to operative position to complete the circuit through the switch.

100 As soon as the motor starts the spark control lever 44 is moved to its normal advanced or partly advanced position and the circuit through the electric starting motor 20 will be interrupted.

105 It will be seen that the improved switch 110

is operated entirely by the movement of the spark control lever 44 and that the need of a separate foot actuated button switch is overcome.

5 The improved switch may be applied to an automobile or the like either during the course of manufacture or at any time thereafter without special skill and without an elaborate alteration of the mechanism of the vehicle. It requires no separate insulation as the blocks 6 and 7 are of insulating material and this greatly reduces the possibility of a short circuit.

15 The improved switch necessitates the movement of the spark control lever to its fully retarded position so that the operator cannot accidentally leave the spark advanced when attempting to start the motor. This overcomes backfiring. This arrangement prevents broken Bendix springs and resultant starter trouble, and a switch constructed in accordance with this invention permits the delivery of more current to the starting motor and as there is only one point 25 of contact arcing, etc., is prevented.

An important feature of the invention resides in the fact that both feet of the operator may be employed for manipulating the foot pedals. This is important in case the 30 motor is accidentally stalled at a street intersection, rail, or grade crossing. In such an event the operator will not have to take his feet off the foot pedals to operate the starter. The operation of the starter is entirely by the spark control lever.

The invention is convenient, easy to operate, and is characterized by simplicity.

The current conducting parts are thoroughly insulated and there is no chance for 40 leaks.

Also, mud and the like is not likely to splash onto the switch.

Figures 5, 6 and 7 illustrate that the invention may be carried out in connection 45 with a Ford automobile having a starting motor 50 provided with the usual Bendix drive and pinion for turning the fly wheel and as this feature is old and well known, no detail illustration of the same appears 50 in the drawing.

Fig. 5 illustrates that the switch may be mounted on the starting motor so that the actuating arm 36 is in the path of travel of the depending arm 40. Therefore, when the rod 41 is turned by the lever 44 the arm 36 will be turned for depressing the member 6 and thereby establishing an electric contact between the parts 10 and 14.

It might be stated that the lower block 7 60 is mounted on a stud bolt or contact screw 10 to which the starting cable is normally attached. Thus the stud 10 not only forms a contact, but also forms a support and attaching means for the switch.

65 Fig. 5 illustrates that the starting cable

is attached to the binding post 14 and the starting cable is connected to one side of the original starting switch 100. In other words, the starting cable is originally connected to opposite sides of the switch 100 and when this invention is employed the starting switch may be either dispensed with entirely or the cable connected to a single side of the starting switch whereby to establish a direct connection between the battery 101 and the binding post 14.

70 It is important to note that the device may be attached to a Ford automobile without altering the parts or interfering with the normal operation of the automobile.

80 Having thus described the invention, what is claimed is:

1. A switch for use in connection with starting motors comprising fixed and movable blocks, a U-shaped leaf spring connecting said fixed and movable blocks, contacts carried by the blocks and adapted for connection with the wires of an electric starting circuit, an actuating bar having a laterally projecting terminal portion engaged with 90 said movable block, an arm for engaging said actuating bar, said arm being provided with means whereby the same may be connected to the spark control rod of an automobile, and a guide member having spaced 95 sides arranged at opposite edges of the movable block to hold the same against lateral movement and cooperating with said movable block in supporting said actuating bar.

2. A switch for use in connection with 100 starting motors comprising a pair of blocks, contacts having connection with the blocks and adapted for connection with the wires of an electric starting circuit, a guide member in the form of a rectangular loop extending about the end portions of said blocks and having a slot, an actuating bar extending through said slot and having a laterally directed terminal portion confined between 110 one of said blocks and the adjacent side of 115 said loop, and a separate arm for contacting with and moving said actuating bar, said arm being provided with means whereby the same may be connected to the spark control rod of an automobile.

3. A starter switch for automobiles comprising a pair of blocks of insulating material, a spring connecting said blocks and normally holding the same in spaced relation, binding posts connected to said blocks 120 and having contacts, said binding posts being adapted for connection with a starting motor, a guide member extending about one of said blocks and holding the same against lateral movement and having a slot, and an actuating bar extending through said slot and having a laterally directed terminal portion confined between one of said blocks and the adjacent side of said guide member.

4. A starting switch for use on automo- 130

biles comprising a member of insulating material having means whereby the same may be connected to a stud bolt of the starting motor on an automobile, a spring connected 5 to said member, a second member connected to said spring and having a binding post adapted for engagement with said stud bolt and having means for connection with a starting cable, an actuating arm associated 10 with said second-named member, and a guide member having spaced sides arranged at opposite edges of said second-named member to hold the same against lateral movement and cooperating with said second- 15 named member in supporting said actuating arm.

5. A starting switch for use on automobiles comprising a member of insulating material having means whereby the same may

be connected to a stud bolt of the starting 20 motor on an automobile, a spring connected to said member, a second member connected to said spring and having a binding post adapted for engagement with said stud bolt and having means for connection with a 25 starting cable, an actuating arm associated with said second-named member, a guide member having spaced sides arranged at opposite edges of said second-named member to hold the same against lateral movement 30 and cooperating with said second-named member in supporting said actuating arm and a second arm adapted to operate said first-named arm and having means whereby the same may be connected to a spark control rod. 35

In testimony whereof I affix my signature.
